GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

PRESSURE-ACTUATED TOOL.

1,053,093.

Specification of Letters Patent. Patented Feb. 11, 1913.

Original application filed November 13, 1908, Serial No. 462,402. Divided and this application filed June 20, 1911. Serial No. 634,281.

To all whom it may concern:

Be it known that I, GEORGE H. GILMAN, a citizen of the United States, and residing at Claremont, county of Sullivan, and State 5 of New Hampshire, have invented an Improvement in Pressure-Actuated Tools, of which the following description, in connection with the accompanying drawings, is a specification, like characters on the drawings representing like parts.

10 This invention relates to tools and consists more particularly in the provision of an improved chuck or tool holder for a pressure-actuated tool.

15 This application is a division of my prior co-pending application, Serial No. 462,402, filed November 13, 1908.

20 My invention will be best understood by reference to the following description when taken in connection with the accompanying illustration of one specific embodiment thereof, while its scope will be more particularly pointed out in the appended claims.

25 In the drawings: Figure 1 shows a plan in detail of the clamp for the tool bushing; Fig. 2 is a transverse section in elevation taken on the line 2--2 in Fig. 1; Fig. 3 shows a central longitudinal section in elevation of the forward end of a hammer drill 30 cylinder to which is applied the tool bushing and clamp shown in Figs. 1 and 2.

Referring to the drawings and the illustrated embodiment of my invention, I have 35 there shown a pneumatic tool, herein of the hammer drill type having the cylinder 1 containing the hammer piston 2 which is adapted to be reciprocated and strike an impact or anvil member 3 resting against the end of the shank of a cutter drill or bit 4. 40 The piston hammer may be of any usual or ordinary type, the construction of the valve and supply ports and passages being of no material concern in connection with the present invention.

45 In the operation of a tool of this type the point of the bit or cutter is pressed against the work, while its opposite end receives the blows delivered by the piston hammer, the cutter bit being permitted longitudinal 50 movement in its holder and being rotatably moved from time to time by the rotation of the tool itself or through other appropriate means. Referring to the holder for the cut-

ter, the shank of the drill 4 preferably passes through a suitable bushing 5 the latter having a bore conforming to the cross section of the drill so as to prevent rotative movement of the drill relatively to the bushing while permitting its longitudinal movement. To prevent either rotative or longitudinal displacement of the bushing, the latter is held fixed in the end of the cylinder by a key bolt 6 lying transversely across the bushing. The key is carried in the split clamping piece 7, which is adapted to be slipped over the end of the cylinder and clamped into position by the key. The walls of the cylinder are transversely cut away to receive the key, and the latter is provided with an inclined bushing-engaging wall 8 adapted to seat in a correspondingly shaped groove or recess in the bushing, so that, when the bolt is clamped up the key seats in the bushing recess and the bushing is locked rigidly against displacement of any kind within the cylinder. 75 By unloosening the clamping nut 9 the key may be moved laterally far enough to permit the removal of the bushing without the withdrawal of the key from the cylinder. Preferably, though not necessarily, the cylinder is split as at 10 for a short distance from its end, so that the bushing can be slipped freely in and out of the cylinder, while, at the same time, it may be clamped tightly within the cylinder when the clamping nut 9 is tightened.

As will be seen from Figs. 2 and 3, the external head of the key bolt is wider than the internal portion 12 on which is formed the inclined engaging wall 8 so that the head bears against the walls of the split clamping piece. It will therefore be observed that the key bolt, by reason of its entrance into the groove or recess in the bushing, holds the latter positively against longitudinal or rotative movement, and at the same time contracts and grips the split clamping piece about the split walls of the cylinder to cause the latter to contract and grip the bushing, a sufficient initial clearance 90 between the wall 8 and the bushing recess being provided to permit a sufficiently forceful gripping action to take place as heretofore referred to.

While I have herein shown and described 105 for the purposes of illustration one concrete

form or embodiment of my invention, it is to be understood that the same is not limited to the details of construction, or relative form or arrangement of parts, or to the application herein made of the various features thereof, but that the same may be modified within wide limits without departing from the spirit of the invention.

Claims.

10. 1. In a pressure-operated tool, the combination of a tool-actuating piston, a cylinder having a bushing-receiving end provided with a lateral transverse key-receiving passage having a non-cylindrical portion, a tool-holding bushing mounted in said cylinder and having provision to hold said tool non-rotative while permitting longitudinal movement thereof, said bushing being provided with a key-receiving recess, and means 70 for clamping said bushing in said cylinder, including a key having a non-cylindrical laterally projecting portion located in said non-cylindrical passage and projecting into its recess, and means to clamp said key 80 therein:
15. 2. In a pressure-operated tool, the combination of a cylinder provided with a bushing-receiving end portion provided with a key-receiving passage, a piston in said cylinder, a tool arranged to receive a longitudinal thrust from said piston, a bushing 85 having provision to hold said tool non-rotative while permitting longitudinal movement thereof, and provided with an inclined lateral recess, and means for holding said bushing fixed including a clamping key located in said passage, having an externally seated shoulder, and a laterally projecting inclined portion located in said recess, and a nut threaded onto said key 95 for drawing the latter into said recess.
20. 3. In a pressure-operated tool, the combination of a cylinder having a contractible bushing-receiving end portion provided with a key-receiving passage, a piston, a tool adapted to receive a longitudinal thrust from said piston, a bushing having provision to hold said tool non-rotative while permitting longitudinal movement thereof, said bushing being provided with a lateral recess, and means to contract said cylinder to grip the bushing therein, including a key located in said passage and having a laterally projecting portion located in said recess.
25. 4. In a pressure-operated tool, the combination of a cylinder having a contractible bushing-receiving end portion provided with a key-receiving passage, a piston, a tool adapted to receive a longitudinal thrust from said piston, a bushing having provision to hold said tool non-rotative while permitting longitudinal movement thereof, said bushing being provided with a lateral recess, and means to contract said cylinder to grip the bushing therein, including a key located in

said passage and having an externally seated head and a laterally projecting portion located in said recess.

5. In a pressure-operated tool, the combination of a cylinder having a contractible bushing-receiving end portion provided with a key receiving passage, a piston, a tool adapted to receive a longitudinal thrust from said piston, a bushing having provision to hold said tool non-rotative while permitting longitudinal movement thereof, said bushing being provided with a lateral recess, and means to contract said cylinder to grip the bushing therein, including a key located in said passage and having an externally-seated head at one end, a reduced screw-threaded shank at its other end, and an intermediate laterally projecting portion located in said recess, and a nut having screw-threaded engagement with said shank. 75

6. In a pressure-operated tool, the combination of a cylinder having a bushing-receiving end portion provided with a key-receiving passage having an enlarged non-cylindrical portion, a piston, a tool adapted to receive a longitudinal thrust from said piston, a bushing having provision to hold said tool non-rotative, while permitting longitudinal movement thereof, said bushing being provided with a lateral recess, a contractible collar, and means to contract said collar to cause the bushing to be gripped, including a key having an externally-seated head and an enlarged non-cylindrical portion located in said non-cylindrical portion of said passage and projecting into said recess. 90

7. In a pressure-operated tool, the combination of a cylinder having a bushing-receiving end portion provided with a key-receiving passage, a piston, a tool adapted to receive a longitudinal thrust from said piston, a bushing having provision to hold said tool non-rotative, while permitting longitudinal movement thereof, said bushing being provided with a lateral recess, a contractible collar, and means to contract said collar to cause the bushing to be gripped, including a key located in said passage and having an externally-seated head at one end, a reduced screw-threaded shank at its other end, and an intermediate enlarged portion located in said recess, and a nut having screw-threaded engagement with said shank. 105

8. In a pressure-operated tool, the combination of a cylinder having a contractible bushing-receiving end portion provided with a key-receiving passage, a piston, a tool adapted to receive a longitudinal thrust from said piston, a bushing having provision to hold said tool non-rotative, while permitting longitudinal movement thereof, said bushing being provided with a lateral recess, and means to contract said cylinder to grip the bushing therein, including a key 110

having a laterally projecting portion located in said recess and locking said bushing against rotative and longitudinal movement.

- 5 9. In a pressure-operated tool, the combination of a cylinder having a contractible bushing-receiving end portion provided with a key-receiving passage having an enlarged non-cylindrical portion, a piston, a 10 tool adapted to receive a longitudinal thrust from said piston, a bushing having provision to hold said tool non-rotative, while permitting longitudinal movement thereof, said bushing being provided with a lateral 15 recess, and means to contract said cylinder to grip the bushing therein, including a key having an enlarged non-cylindrical portion located in said non-cylindrical portion of said passage and projecting into said recess and locking said bushing against rotative as well as longitudinal movement.
- 10 10. In a pressure-operated tool, the combination of a cylinder having a contractible bushing-receiving end portion provided with a key-receiving passage, a piston, a 15 tool adapted to receive a longitudinal thrust from said piston, a bushing having provision to hold said tool non-rotative, while permitting longitudinal movement thereof,

30 said bushing being provided with a lateral recess, and means to contract said cylinder to grip the bushing therein, including a contractible collar, a key located in said passage and having an externally-seated head and a portion non-rotatively engaged in said cylinder and located in said recess.

35 11. In a pressure-operated tool, the combination of a cylinder having a bushing-receiving end portion provided with a non-cylindrical key-receiving passage, a piston, a 40 tool adapted to receive a longitudinal thrust from said piston, a bushing having provision to hold said tool non-rotative, while permitting longitudinal movement thereof, said bushing being provided with a lateral 45 recess, a contractible collar, and means to contract said collar to cause the bushing to be gripped, including a key having a non-cylindrical portion located in said passage and projecting into said recess.

50 In testimony whereof, I have signed my name to this specification, in the presence of two subscribing witnesses.

GEORGE H. GILMAN.
